UNITED STATES PATENT OFFICE

LEON HEHL ASHMORE, OF COLLINGSWOOD, NEW JERSEY, ASSIGNOR TO THE ESTER-BROOK STEEL PEN MANUFACTURING CO., OF CAMDEN, NEW JERSEY, A CORPORATION OF NEW JERSEY

FOUNTAIN PEN

Application filed July 13, 1931. Serial No. 550,353.

My invention relates to fountain pens, and one object is to provide a novel and inexpensive construction permitting ready assembly of the necessary pen points therewith and renewal of the same in a simple and efficient manner and without disturbing the feed bar or the ink-supplying means.

A further object of my invention is to provide a construction that will permit the use of pens of any ordinary type and material, including those made of stainless steel and/or the like.

And a further object of my invention is to provide a construction whereby the groove of the feed-bar will be sealed by the shank of the pen, and the latter firmly held in its proper place and in the sealing position.

These and other features of my invention are more fully described hereinafter; reference being had to the accompanying drawings, in which:

Figure 1 is a longitudinal sectional view of the writing end of a fountain pen constructed in accordance with my invention.

Fig. 2 is an enlarged longitudinal sectional view of a portion of the same.

Fig. 3 is a plan view of a portion of the structure shown in Fig. 2.

Fig. 4 is a cross-sectional view on the line IV-IV, Fig. 2.

Figs. 5 and 6 are plan views similar to Fig. 3, illustrating modified details of my invention.

Fig. 7 is a fragmentary view, showing in sectional elevation the modified construction illustrated in Fig. 6.

Fig. 8 is a longitudinal sectional elevation similar to Fig. 2 of a further modification within the scope of my invention.

Figs. 9, 10 and 11 are views similar to Fig. 3, illustrating modified forms of pens which I may employ, and

Figs. 12 and 13, are cross sectional views, similar to Fig. 4, illustrating further modifications within the scope of my invention.

It is the common practice, in the construction of fountain pens, to assemble the pen element in permanent position with respect to the feed-bar, and then to mount the combined pen and feed-bar in permanent relation

to the barrel of the fountain pen. The pens so mounted are usually of gold, and any change required by reason of damage or otherwise, required expert work in the factory.

In the construction of the present fountain pen structure, I propose to use ordinary pens made of any material; any suitable metal, stainless steel and/or the like, and the feature of my invention is to provide a construction that will permit ready renewal of these pens as occasion may require in a simple and efficient manner without in any way affecting the operation of the fountain pen or disturbing the position of the feed-bar and additionally insuring that such pens will seal the ink groove of the feed bar and prevent leakage.

The construction is such that the user of the pen may renew the pen as often as desired, without effort and without staining the fingers with ink, and with the assurance that the structure will operate perfectly as soon as a fresh pen is positioned. Such positioning is entirely automatic and when the retaining member is in place the pen is ready for use. The construction also permits ready

cleansing of the ink groove of the feed-bar, should occasion require. It will be understood of course that the usual gold pens may be employed, if desired.

In the drawings, 1 represents the shell or barrel of the fountain pen which may be of any usual construction; being threaded at 1^a for the reception of the usual cap (not shown). Fitted in the end of this shell in any suitable manner, shown in the drawings as a sliding fit, is a sleeve member 2, to which the ink bag 3 is attached; such sleeve member also receiving in tight permanent engagement, usually a sliding fit, a feed bar 4, provided with the usual slot or groove 4^a, or other opening, for the passage of ink to the pen.

The upper portion of the outer end of the sleeve member 2, considering the position of the parts as illustrated in Figs. 1 and 2, is cut away as indicated at 2^a, exposing a portion of the feed bar 4, and this exposed portion of the feed bar, which may have a substantially semi-circular contour or sur-

face, as clearly indicated in Fig. 4, receives the shank of the pen indicated at 5. And such shank may be semi-circular in cross section, as shown in Fig. 4, to accurately fit 5 the feed-bar.

In such position, the shank of the pen overlies the ink groove 4^a of the feed-bar, and the end of such shank engages the wall or shoulder 2^b of the cut away portion of the sleeve member 2; making close contact therewith and sealing the ink groove. The pen employed is provided with an engaging portion which may be in the form of a boss or projection 6 struck up from the body of the 15 same, as clearly illustrated in the drawings, and the pen is retained in place and properly positioned with respect to the feed bar by means of a hollow cap member 7, threaded onto the end of the sleeve member 2; such 20 cap member fully enclosing and covering the cut away portion of the sleeve member. The hollow cap member is internally shouldered at 7^a, and when it is finally seated in position, this internal shoulder engages and partly 25 rides on the engaging portion of the pen, which may be the projection 6, and forces the latter rearwardly; jamming it in contact with the wall 2^b of the sleeve member 2, and closing the ink groove 4^a of the feed-bar 4. Additionally, this engagement of the cap member 30 7 presses the pen into close contact with the feed-bar over said ink groove 4^a and prevents any leakage of ink. The cap member is readily removable for the insertion of a 35 fresh pen of any suitable type, but with a properly shaped shank, which may be positioned in the manner indicated at any time by the user of the pen.

While the end of the pen shank is shown 40 as rounded in Fig. 2, it may be slightly flattened as indicated at 5^a, Fig. 5, for engagement with the shoulder or wall 2^b of the sleeve member 2, so as to further insure the sealing of the ink groove of the feed-bar.

45 In lieu of this arrangement, the sleeve member 2 may be slightly recessed, as indicated at 2^c, Figs. 6 and 7, so as to permit the end of the pen shank to fit into the same.

It will be understood, of course, that pens 50 of any type, having shanks of the proper size and contour fitting the feed-bar may be employed in any of the constructions illustrated, and that the shanks of such pens will have a 55 contour or shape exactly fitting the surface of the feed-bar; thereby insuring closure of the ink groove.

In the broader aspect of my invention, which comprises an improved construction 60 permitting ready separation of certain parts of the fountain pen structure to replace a pen, it is not necessary that the feed-bar be of a construction requiring the pen to cover the ink groove thereof, and in Fig. 8, I have shown a feed-bar 40 having a bored or drilled 65 ink passage 40^a. In the connection with this

arrangement I have shown a relatively deep recess 40^b at the end of the ink passage directly underlying the opening usually provided in pens; insuring proper feed of ink. This recess or reservoir may also be employed 70 with the type of feed-bars shown in the other views.

I do not wish to be limited to the use of a boss such as indicated at 6, as the part engaged by the cap member 7 and in Fig. 9 I 75 have shown a pen 50 having a transverse rib or projection 60, which may be engaged by the internal shoulder 7^a of the cap member 7. As a further modification I may employ a plurality of bosses, as indicated at 60^a, Fig. 80 11.

While I prefer to use pens having relatively straight shanks as illustrated in Figs. 2, 3, et seq., I may use pens having tapered shanks; a construction familiarly found in 85 gold pens, and in Fig. 10 I have shown a pen 51 of this type, having a single boss or projection 61^a. It will be understood of course that pens having these tapered shanks may be provided with a transverse rib, such as 90 shown in Fig. 9, or the plurality of bosses shown in Fig. 11.

In general a pen with a shank of semi-circular contour is preferable, but I do not wish to be limited to such construction and 95 other forms are illustrated in Figs. 12 and 13. In Fig. 12, I have shown a feed-bar slightly flattened as at 4^b and the pen shank has a flattened portion constructed to closely fit the same. In Fig. 13 the pen shank is 100 shown as provided with a rounded rib on its underside, which rib is aligned with the ink groove 4^a and additionally serves to make close contact with the feed bar and seal such groove. 105

The inner wall of the sleeve member 2 engages the pen shank and insures its assumption of the right position with respect to the feed-bar, and also prevents the pen moving out of position with respect to the feed-bar. 110

I claim:

1. A fountain pen comprising a barrel having ink supplying means, a tubular sleeve therefor, a feed-bar permanently associated with said tubular sleeve; the latter being 115 partly cut away to expose a portion of the feed-bar, a pen arranged to overlie the feed-bar and extend over the portion exposed by the tubular sleeve, and a cap in threaded engagement with said sleeve adapted to overlie said pen and secure the same in place.

2. In a structure such as set forth in claim 1, a pen having a portion engaged by the cap whereby end thrust may be imparted to said pen. 125

3. In a structure such as set forth in claim 1, a pen having a struck-up projection engaged by the cap whereby end thrust may be imparted to said pen.

4. A fountain pen comprising a barrel hav-

130

ing ink supplying means, a tubular sleeve therefor, a feed-bar permanently associated with said tubular sleeve; the latter having a threaded extension and being partly cut away 5 to expose a portion of the feed-bar, a pen arranged to overlie the feed bar in the portion exposed by the tubular sleeve, and a cap secured to the threaded extension of the tubular sleeve and adapted to overlie said pen and 10 secure the same in place.

5. A fountain pen comprising a barrel, a tubular sleeve therefor carrying ink supplying means, a feed-bar with an open ink groove permanently associated with said tubular 15 sleeve; the latter having a threaded extension and being partly cut away to expose a portion of the feed bar, a pen removably arranged to overlie the ink groove of the feed-bar, and a detachable cap adapted to overlie said pen 20 and secure the same in place and seal said ink groove.

6. A fountain pen comprising a barrel having ink supplying means, a tubular sleeve therefor, a feed-bar having an ink groove 25 permanently associated with said tubular sleeve; the latter having a threaded extension and being partly cut away to expose a portion of the feed-bar and the ink groove thereof, a pen arranged to overlie the feed-bar and 30 within the portion exposed by the tubular sleeve; said ink groove being sealed by said pen, and a cap adapted to overlie said pen and secure the same in place and cooperating to hold the pen in tight engagement with the 35 feed-bar over the ink groove thereof.

7. In a structure such as set forth in claim 6, a pen having a portion engaged by the cap whereby endwise and downward thrust may be imparted to said pen.

40 8. In a structure such as set forth in claim 6, a pen having an integral struck-up projecting portion engaged by the cap whereby endwise and downward thrust may be imparted to said pen.

45 9. In a structure such as set forth in claim 6, a tubular sleeve having a recess receiving the end of the pen shank.

10. In a structure such as set forth in claim 6, a feed-bar having a flattened surface adjacent the ink groove, and a pen having a 50 shank conforming to said flattened surface.

11. In a structure such as set forth in claim 6, a pen having a shank with a longitudinal rib on its under surface aligned with and 55 engaging the edges only of the ink groove.

In witness whereof I have signed this specification.

LEON HEHL ASHMORE.
